UNITED STATES PATENT OFFICE

2,458,248

HAND DRIVEN DEVICE

Ramon Bujan, New York, N. Y.

Application July 26, 1946, Serial No. 686,496

2 Claims. (Cl. 74—130)

1

This invention relates generally to a hand driven fan, but more specifically to a hand driven mechanism arranged for rotating a shaft.

The main object of the invention resides in the provision of the combination of such a type of mechanism with a cooperating housing therefor.

Another object of the invention resides in the provision of a mechanism operable by finger movement to impart rotary motion to a shaft having a fan or similar attachment secured thereto.

A further object of the invention resides in the provision of a device of the character described and characterized by being noiseless in operation.

Another object of the invention resides in the provision of a durable, strong and efficient hand driven device for fan operation which device is economical to manufacture and aesthetic in appearance.

These objects and other incidental ends and advantages of the invention will hereinafter appear in the progress of the disclosure and as pointed out in the appended claims.

Accompanying this specification are drawings showing a preferred form of the invention wherein corresponding reference characters designate corresponding parts throughout the several views and wherein:

Figure 1 is a plan view of an open ended housing member showing the location of openings to mount the mechanism of the device.

Figure 2 is a longitudinal sectional view taken along the plane 2—2 of Figure 1.

Figure 3 is a plan view with the mechanism of the device mounted in the housing and showing the actuating rack in uppermost position.

Figure 4 is a plan view of the mechanism shown in Figure 3 showing the actuating rack in depressed and lowermost position.

Figure 5 is a longitudinal sectional view taken along the plane 5—5 of Figure 3.

Figure 6 is a transverse sectional view taken along the plane 6—6 of Figure 3.

Figure 7 is a side view in elevation partly broken away and partly sectioned showing the assembly of the housing, the mechanism mounted therein of the housing cover member.

Figure 8 is a view in perspective showing a fan attachment actuated by the hand driven mechanism.

In accordance with the invention and the preferred form shown in the drawings a main housing generally indicated by numeral 10 is provided and as shown is in the form of a cap member having a bottom wall 11 and a cylindrical side

2

wall 12. The upper face of bottom wall 11 is provided with a diametrically disposed rectangularly shaped raised portion or strip 13, both the strip and the bottom wall 12 being provided with a recess and openings for the mounting of the mechanism as will hereinafter appear. In addition the cylindrical wall 12 is also formed with a notch 19 to permit freedom of reciprocation of one of the members of the mechanism as will also hereinafter appear. It is to be observed that housing 10 is constructed in a manner whereby it may be cast from one piece of material such as metal, plastic or other suitable substance.

In bottom wall 11 and on strip 13 are openings 14, 15, 17 and 18 for rivets used to fasten the mechanism to the housing 10. A recess 16 is formed centrally of bottom wall 11 passing through strip 13 to serve as the lower bearing for a rotatable shaft hereinafter to be described.

20 A notch 19 is provided in circular wall 12 for reciprocation therethrough of an operable member for the device such as a rack 29 in the form of an inverted U-shaped element having legs 30 and 31, the said rack having a finger engaging boss 32 at the top thereof and a series of teeth 33 along the lower half of the external side of one of the rack legs 30 to engage a pinion 37 as will hereinafter appear.

Mounting means for the mechanism include 30 a bracket 20 spaced from and secured to housing wall 11 by means of an upright 21, the said upright being secured to wall 11 through openings 15 as by rivets 22 and 23, respectively. Intermediate bracket 20 is an opening 24 and at the bracket end is another opening 25. Beneath bracket 20 is a plate 26 superposing and secured to strip 13 as by rivets 27 and 28, the rivets passing through the strip openings 17 and 18. Plate 26 is also provided with an intermediate opening 26a in registration with bracket opening 24 and recess 16. It will now be seen how bracket 20, strip 13 and plate 26 in conjunction with housing wall 11 serve as the mounting means for the hand operable rack 29 acting on a train of gears to effectuate a unidirectional rotary movement of a shaft 41 to which may be attached fan blades 48 or other mechanism adapted to be driven by shaft 41.

50 Thus, a gear 35 having teeth 34 is secured to the upper end of a shaft 36, the shaft 36 being rotatably mounted between bracket opening 25 and wall opening 14. Rotatably mounted on shaft 36 between the undersurface of gear 35 and the inner face of housing wall 11 is a pinion 55 37 carrying an enlarged ratchet wheel 38 at the

top, the teeth of said ratchet wheel being engageable by a pawl 39 secured to the underside of gear 35 as by a pivot 40 as best seen in Figure 5.

The shaft 41 which is rotatably mounted between bracket opening 24, plate opening 26a and bearing recess 16 has formed therewith a pinion 42 below bracket 20 to engage with teeth 34 of gear 35 as best seen in Figure 5.

To maintain rack 29 in normally extended position, a compression spring 43 is secured at one end to a lug 44 at the upper edge of plate 26 and at the other end is secured to a screw 45 engaging rack leg 31 adjacent the end thereof.

Upon finger compression on rack boss 32 against the force of spring 43, teeth 33 on rack leg 30 causes rotation of pinion 37 in a clockwise direction, said movement being translated to gear 35 by engagement between a tooth of ratchet 38 and the pawl 39. Shaft 41 is thereby made to rotate in a counterclockwise direction by the engagement between gear teeth 34 and the shaft pinion 42. Upon release of pressure on boss 32, spring 43 forces the rack to return to normal extended position, the counterclockwise movement of pinion 37 not being translated to gear teeth 34 because of the sliding engagement between the ratchet 38 and the pawl 39. Thus, on the return movement of rack 29, shaft 41 does not rotate. It becomes obvious that by repeating the downward thrusts on rack boss 32, shaft 41 rotates intermittently in a counterclockwise direction only.

It is to be observed that the side edges of strip 43 engaging the inner edges of rack legs 30 and 31 and the inner and upper faces of plate 26 and wall 11, respectively, engaging the upper and lower faces of the legs 30 and 31 maintain the axial motion of the reciprocable rack in the same plane.

Moreover, edge 29a of rack 29 engages the upper edge of strip 43 to serve as a stop for downward motion of the rack, while screw 45 engages one of the lateral shoulders 26a of plate 26 to serve as a stop for the upward motion of the rack.

A cover member 47 is suitably secured as by an adhesive to the free edge of the cylindrical wall 12 to conceal the mechanism as seen in Figures 7 and 8, the rack 29 protruding from wall 12 through the slot 19. As shown, the outer end of rack 29 may be provided with an opening 46 for securing the assembly to a string or chain for carrying purposes.

I wish it understood that minor changes and variations in the integration, location, material and substitution of parts may all be resorted to without departing from the spirit of the invention and the scope of the appended claims.

I claim:

1. In a hand-driven device, a frame comprising a casing, a bottom wall therefor provided with an integral guide ridge, a hand-actuated rack member slidably engaging said bottom wall and the side walls of said ridge to be guided thereby, a side wall, connected to the casing penetrated by said rack member, a top bearing plate for said rack member secured to the casing bottom wall and the ridge thereof, a bracket secured to said casing bottom wall and extending at an angle to the guide ridge and elevated therefrom, a central rotatable shaft projecting above the casing and mounted between the bracket and the casing bottom wall and journaled in the guide ridge thereof, a second rotatable shaft mounted between the bracket and the casing bottom wall, gear and pinion means on and operatively connecting said shafts, ratchet means on one of the shafts, a cover member for said casing penetrated by the central shaft, spring means between the rack and a stationary portion of the frame to normally maintain the rack in outermost extended position beyond the casing side wall, the downward movement of the said rack actuating the gear and pinion means to cause rotation of the central shaft and the return upward movement of said rack being operative on the ratchet means rendering the central shaft stationary.

2. In a hand-driven device, a frame comprising a casing, a bottom wall therefor provided with an integral guide ridge, a hand-actuated rack member slidably engaging said bottom wall and the side walls of said ridge to be guided thereby, a side wall penetrated by the rack member, a top bearing plate for said rack member secured to the bottom wall and to the ridge thereof, a bracket secured to said bottom wall and one side of the ridge and intersecting the ridge at an elevated location thereover, a central rotatable shaft projecting above the casing and mounted between the bracket and bottom wall and journaled in the ridge thereof, a second rotatable shaft between the bracket and the bottom wall, a gear train between the shafts actuatable by downward movement of the rack to cause rotation of the central shaft, and spring means between the rack and a stationary portion of the frame to normally maintain the rack in outermost extended position beyond the casing side wall.

RAMON BUJAN.
